UNITED STATES PATENT OFFICE

172,264

SURGICAL LUMINAIRE

Richard C. Berry and Joseph W. Spradling, Madison, Wis., assignors to Air Reduction Company, Incorporated, New York, N. Y., a corporation of New York

Application June 25, 1953, Serial No. 25,665

Term of patent 14 years

(Cl. D48—20)

To all whom it may concern:

Be it known that we, Richard C. Berry and Joseph W. Spradling, a citizen of United States, residing at Madison, county of Dane, State of Wisconsin, and a citizen of United States, residing at Madison, county of Dane, State of Wisconsin, respectively, have invented a new, original, and ornamental Design for a Surgical Luminaire, of which the following is a specification, reference being had to the accompanying drawings, forming a part hereof.

Fig. 1 is a side perspective view of a surgical luminaire, showing our new design;

Fig. 2 is a side perspective view showing the reflector in canted position; and

Fig. 3 is a perspective view looking at the right end of Fig. 1.

We claim:

The ornamental design for a surgical luminaire, as shown.
